US00D624013S

(12) **United States Design Patent**
Lingott

(10) **Patent No.:** **US D624,013 S**
(45) **Date of Patent:** **** Sep. 21, 2010**

(54) **BATTERY CHARGER**

(75) Inventor: **Philippe Lingott**, Essen (DE)

(73) Assignee: **Robert Bosch GmbH**, Stuttgart (DE)

(**) Term: **14 Years**

(21) Appl. No.: **29/359,351**

(22) Filed: **Apr. 9, 2010**

(30) **Foreign Application Priority Data**

Nov. 18, 2009 (EM) 001178818

(51) **LOC (9) Cl.** **13-02**

(52) **U.S. Cl.** **D13/107**

(57) **CLAIM**

The ornamental design for the battery charger, as shown and described.

DESCRIPTION

FIG. 1 is a right elevational view of the battery charger;

FIG. 2 is a left elevational view thereof;

FIG. 3 is a front elevational view thereof;

FIG. 4 is a rear elevational view thereof;

FIG. 5 is a top plan view thereof; and,

FIG. 6 is a bottom plan view thereof.

The broken lines are for the purpose of illustrating environmental structure and form no part of the claimed design.
